(57) **CLAIM**

The ornamental design for a neonatal and head medical imaging scanner, as shown and described.

DESCRIPTION

FIG. 1 is a perspective view of a neonatal and head medical imaging scanner having a design thereon in accordance with an embodiment of the present invention.

FIG. 2 is a side elevational view of the neonatal and head medical imaging scanner of FIG. 1.

FIG. 3 is a front elevational view of the neonatal and head medical imaging scanner of FIG. 1.

FIG. 4 is a top plan view of the neonatal and head medical imaging scanner of FIG. 1; and,

FIG. 5 is a rear elevational view of the neonatal and head medical imaging scanner of FIG. 1.

The broken lines in the drawing views are included for the purpose of illustrating portions of the neonatal and head medical imaging scanner that form no part of the claimed design.
